UNITED STATES PATENT OFFICE.

WISNER B. BISBEE, OF LOWELL, MASSACHUSETTS, ASSIGNOR TO FREDERICK TAYLOR, OF SAME PLACE.

COAT-HANGER.

SPECIFICATION forming part of Letters Patent No. 374,035, dated November 29, 1887.

Application filed March 7, 1884. Serial No. 123,329. (No model.)

To all whom it may concern:

Be it known that I, WISNER B. BISBEE, a citizen of the United States, residing at Lowell, in the county of Middlesex and Commonwealth of Massachusetts, have invented certain new and useful Improvements in Coat-Hangers, of which the following is a specification.

My invention relates to a coat-hanger, formed, preferably, of wire, and to means whereby the same may be folded into small compass.

In the accompanying drawings, Figure 1 is a perspective view of a folding coat-hanger provided with a hat-hook, the hanger being extended ready for use; Fig. 2, a perspective view of the same folded for transportation; Fig. 3, a top view of the same extended, the dotted lines indicating different positions of the supporting-hook and hat-hook; Figs. 4 and 5, respectively, a side and a front elevation of the coil or hinge detached; Fig. 6, a front elevation of the coil or hinge detached and folded; Fig. 7, a front view of the divided brace and locking tube or sleeve; Fig. 8, a front elevation of a modified form of my invention.

The invention herein shown and described is an improvement on the coat-hanger which forms the subject of United States Letters Patent No. 254,451, granted to me March 7, 1882. The suspending-hook C, connected by a swivel or socket, F, to the hanger, the shoulder pieces or loops A A, extended from front to back to form a broad bearing for garments suspended thereon, and each provided with a twist, V, at the ends of the loops, the hat-hook T, swinging in the coil E, and the half-circle Y are all substantially as shown and described in said patent. The brace B serves the same purpose when the hanger is in use as the corresponding part in said patent, but in this invention is divided into two unequal parts, b b', so that one shoulder-piece may be turned around over the other; the parts or separate wires of the coil E slipping upon each other and turning about the shank P of the hat-hook T as about the pintle of a hinge.

In order that the hanger may fold until one shoulder-piece is entirely over the other, only one half-circle Y is used, instead of the two

shown in said patent, and the parts D D of the wires which connect the shoulder-pieces and the coil E are connected to the bottom of the coil E in such a manner as to be, when the coat-hanger is extended, in the same vertical plane with each other and with the half-circle Y, and therefore both on the same side of the shank of the hook C and shank of the hook T, the relative position of said parts D D being shown in Figs. 4 and 5. The wires of the coil E being wound spirally, the act of folding the hanger will cause one of the shoulder-pieces to be raised above the other and to overlie the other, the shoulder-pieces coming again to their normal position and the adjacent ends of the parts b b' of the brace B coming into line with each other when the hanger is subsequently extended for use. When the hanger has been so extended, the tube b², surrounding the longer part b of the brace, is pushed over the joint or adjacent ends of the parts of the brace, as shown in Figs. 1 and 7, and stiffens the brace.

In the modification shown in Fig. 8 the socket F, half-circle Y, and the hat-hook T are omitted, and the coil E serves as a socket for the suspending-hook, and, with the shank of said hook as a pintle, also forms the hinge which connects the halves of the hanger. In other respects the hanger shown in Fig. 8 is like that shown in Figs. 1, 2, and 3, and above described.

The advantage to travelers of a coat-hanger that shall occupy small space in a trunk or valise, and which, when in use, is of proper size and as firmly braced as the ordinary hanger, is obvious.

I claim as my invention—

1. The combination of the shoulder-pieces, a pintle, and two spiral coils, one united to each shoulder-piece, said coils being adapted to turn upon each other around said pintle, as and for the purpose specified.

2. The combination of the shoulder-pieces, the divided brace, the locking-tube, and a hinge connecting said shoulder-pieces, as and for the purpose specified.

WISNER B. BISBEE.
